UNITED STATES PATENT OFFICE.

WILLIAM F. FALLON, OF CLEVELAND, OHIO.

DESIGN FOR A CAR-SEALER'S TOOL.

SPECIFICATION forming part of Design No. 25,883, dated August 4, 1896.

Application filed May 14, 1896. Serial No. 591,586. Term of patent 14 years.

To all whom it may concern:

Be it known that I, WILLIAM F. FALLON, a citizen of the United States, and a resident of Cleveland, county of Cuyahoga, State of Ohio, have invented a new and original Design for a Car-Sealer's Tool, of which the following is a specification, reference being had to the accompanying drawings, showing a part thereof.

In the views, Figure 1 is a plan view of the tool, showing my design. Fig. 2 is a side elevation of the same. Fig. 3 shows a view of one end, and Fig. 4 is a view of the other end.

In general design the tool is of T shape with cylindrical body 1 and cross-piece 2. The extremities of the cross-piece are one rectangular at 3 and the other transversely wedge-shaped at 4. A V-shaped notch 5 is cut in this extremity. The extremity of the body portion 1 opposite to the cross-piece is broadened and flattened at 6, continuing the outline of the

body portion in the edge view, but considerably broader in the plan view, where its edges are united with the body portion by inwardly curved lines 7. Centrally in the plan view is seen a stirrup-shaped opening 8, cutting the flat portion transversely, and in Fig. 4 is seen an opening 9 through the body of the flat portion, which extends into the stirrup-shaped opening. This opening 9 is provided with parallel sides 10, connected at either extremity 25 of the opening by semicircular arcs, and the opening is elongated, the length being twice the width.

What I claim is—

The design for a car-sealer's tool, substantially as shown and described.

WILLIAM F. FALLON.
